United States Patent

Des. 239,184

Patented Mar. 16, 1976

239,184

DOLL

Zula B. Cox, Rte. 1, Box 5A, Folsom, La. 70436

Filed Oct. 26, 1973, Ser. No. 410,287

Term of patent 14 years

Int. Cl. D21—01

U.S. Cl. D34—4 R

FIG. 1

FIG. 2

FIG. 1 is a front elevational view of a doll showing my new design; and

FIG. 2 is a rear elevational view thereof.

The characteristic features of the design reside in the costume.

I claim:

The ornamental design for a doll, substantially as shown and described.
